UNITED STATES PATENT OFFICE.

CORNELIUS J. RYAN, OF MERIDEN, CONNECTICUT.

CAP-REMOVER.

1,347,410.

Specification of Letters Patent.

Patented July 20, 1920.

Application filed December 6, 1919. Serial No. 342,888.

To all whom it may concern:

Be it known that I, CORNELIUS J. RYAN, a citizen of the United States, residing at Meriden, in the county of New Haven and 5 State of Connecticut, have invented new and useful Improvements in Cap-Removers, of which the following is a specification.

This invention comprehends the provision of a device by means of which milk bottle 10 disks can be readily and easily removed without handling the disk, the device being designed to provide a sanitary cover or closure for the bottle subsequent to the removal of the disk.

15 To this end, the invention makes use of a cap which supports an element adapted to penetrate the disk of the milk bottle, for the purpose of removing the disk from the bottle, in combination with means whereby 20 the disk is forced from the said element subsequent to its removal from the bottle, while the cap is designed to fit the mouth of the bottle in a manner to prevent dust, dirt and other foreign matter from collecting around 25 the mouth or shoulder of the bottle which supports the disk.

With these and other objects in view, the nature and advantages of the invention will be better understood when the following detail 30 description is taken in connection with the accompanying drawings, the invention residing in the construction, combination and arrangement of parts as claimed.

In the drawings forming part of this 35 specification like numerals of reference indicate similar parts in the several views and wherein:—

Figure 1 is a fragmentary portion of a milk bottle.

40 Fig. 2 is a top plan view.

Fig. 3 is a vertical sectional view through Fig. 1.

Fig. 4 is a bottom plan view of the attachment showing the subject matter of the 45 invention.

Referring to the drawings in detail, 10 indicates a milk bottle of usual construction provided with the disk 11 constituting a closure therefor.

50 The device forming the subject matter of my invention comprises, a cap 12 designed to embrace the mouth of the bottle in a manner shown in Fig. 1. The cap 12 is provided with a central opening through 55 which the plunger 13 slidably projects, the plunger terminating to provide a pointed

extremity in the shape of an arrow indicated at 14. The plunger is supported by means of a plate 15 which has a central opening through which the plunger projects, the plate 15 being arranged above or exteriorly of the cap 12. Depending from the plate 15 are pins 16 which also slide through openings 17 in the cap 12, these pins being associated with and supporting a 60 similar plate 18 within the cap as shown. Coiled springs 19 which bear against the top of the cap 12 and secured to the pins 16 in a manner whereby the plate 15 is normally maintained elevated in spaced relation to the cap 12, while the plate 18 is disposed in engagement with the underside of the cap.

In practice, the cap 12 is positioned upon the mouth of the bottle in a manner shown 75 in Fig. 1, subsequent to which the plunger 13 is depressed causing the arrow 14 to penetrate the disk 11. The arrow is then slightly turned to position the arrow 14 with respect to the opening made in the disk 11 80 so that the proper purchase may be had upon the disk 11 to remove the same from the bottle with the separation of the cap 12 therefrom. With the cap separated from the bottle and the disk 11 supported upon 85 the plunger, the plate 15 is depressed against the tension of the springs 19, this action forcing the plate 18 against the disk 11 for the purpose of removing or forcing the disk 11 from the plunger 13. After this has 90 been accomplished, the cap 12 is placed upon the mouth of the bottle, and by reason of the configuration of the cap, it is apparent that dust and other foreign matter, is prohibited from collecting about the mouth of 95 the bottle or the shoulder upon which the disk 11 was originally mounted. The device in its entirety is simple in construction and can be conveniently manipulated for the purpose intended without at any time handling the disk 11, or removing the same 100 from the bottle, thus overcoming the objectionable practice or custom of forcing the disk 11 partly within the bottle when it is desired to remove the same.

105 This practice is very unsanitary for well known reasons.

While I have shown and described what I consider the preferred embodiment of the invention, I desire to have it understood that 110 the same is merely illustrative, and that I do not limit myself to any of the details of

construction, inasmuch as such changes may be resorted to when desired as fall within the scope of what is claimed.

Having thus described my invention what I claim as new is:—

1. A device of the class described comprising a cap, designed to fit the mouth of the milk bottle, means supported by the cap for engaging and removing the disk 10 from the bottle, and means carried by the cap for separating the disk from the aforementioned means as described.

2. The combination with a milk bottle having a disk closure therefor, of a cap 15 adapted to fit the mouth of the bottle, a plunger supported by the cap and adapted to penetrate the disk, engaging the latter to remove the disk from the bottle, and means carried by the cap for forcing the disk from 20 the plunger, subsequent to separation of the cap from the bottle.

3. The combination with a milk bottle and disk closure therefor, of a cap designed to fit the mouth of the bottle, a plunger carried by the cap and adapted to penetrate said disk, engaging the latter to remove the disk from the bottle upon removal of the cap therefrom, and yieldably supported means carried by the cap and associated 25 with the plunger to force the disk from the plunger as described.

4. The combination with a milk bottle

having a disk closure therefor, of a cap designed to fit the mouth of the bottle, a plunger supported by said cap and adapted to 35 penetrate said disk to engage the latter and remove the disk from the bottle upon separation of the cap therefrom, a plate disposed within said cap and slidably mounted upon the plunger for removing the disk from the 40 plunger, and yieldable means for supporting said plate.

5. The combination with a milk bottle having a disk closure, of a cap designed to fit the mouth of the bottle, a plunger carried 45 by the cap and adapted to penetrate the disk to remove the same from the bottle, upon separation of the cap therefrom, a pair of spaced plates slidably mounted on the plunger, said plates being disposed at opposite 50 sides of the cap, yieldable means supporting said plate, one of said plates being adapted to be depressed by the fingers to move the other of said plates into engagement with the disk for removing the latter from the 55 plunger.

6. A device of the class described comprising a support, means carried by the support for engaging and removing a bottle closure, and means forming a part of the 60 device for separating the closure from the first mentioned means.

In testimony whereof I affix my signature.
CORNELIUS J. RYAN.
